Philip K. Curran & Fish

UNITED STATES PATENT OFFICE.

WILLIAM H. RANKIN, OF WALTHAM, MASSACHUSETTS.

WEFT-REPLENISHING LOOM.

1,187,093.

Specification of Letters Patent. Patented June 13, 1916.

Application filed June 10, 1915. Serial No. 33,369.

To all whom it may concern:

Be it known that I, WILLIAM H. RANKIN, a citizen of the United States, residing at Waltham, in the county of Middlesex and 5 State of Massachusetts, have invented certain new and useful Improvements in Weft-Replenishing Looms; and I do hereby declare the following to be a full, clear, and exact description of the invention, such as 10 will enable others skilled in the art to which it appertains to make and use the same.

The present invention relates to improvements in weft replenishing looms and more particularly to improvements in the filling 15 feeler mechanism and transerrer devices for such looms.

The usual construction of automatic weft replenishing looms is such that, after the exhaustion of the filling in the active shuttle 20 to a predetermined extent and the operation of the filling detecting mechanism in ascertaining that exhaustion, it is necessary for the shuttle to make at least one traverse through the shed before the insertion of a 25 fresh supply of filling in the shuttle. The disadvantages of this mode of operation are that the filling is liable to be completely exhausted before the shuttle reaches its shuttle box on the filling-supply side of the 30 loom, with the result that short wefts are often woven into the cloth, thereby impairing its quality. In Letters Patent No. 1,184,063, dated March 30, 1915, provision was made for feeling for the filling in the 35 active shuttle and determining the state of its exhaustion during the first part of the forward movement of the lay while the shuttle was in its box on the filling replenishing side of the loom and, thereafter, effecting the insertion of a fresh supply of 40 filling in the shuttle on the same forward beat of the lay.

The advantages of detecting the amount of filling in the active shuttle and on the 45 critical exhaustion of the same to cause the insertion of a fresh supply of filling in the shuttle on the same beat of the lay, are obvious, but the mechanism for effecting this has hitherto been somewhat complicated.

50 The object of the present invention, therefore, is to simplify the construction of weft replenishing looms in which a fresh supply of filling is inserted into the active shuttle on the same beat of the lay on which the detection of critical exhaustion takes place,

and to render such construction more effective and less liable to get out of order.

To this end one feature of the invention contemplates positioning the transerrer devices rearwardly of the filling magazine and arranging their parts in such manner that they will be actuated not, as hitherto has been customary, by the lay, but by a cam driven in timed relation to the lay motion.

Another feature of the invention contemplates transferring a fresh supply of filling to the active shuttle while the lay is on its forward center by a transerrer located rearwardly of the lay.

A further feature of the invention resides in so arranging the parts of the filling feeler mechanism and transerrer devices and determining the timing of their operations that the filling feeling takes place just previous to the arrival of the lay at its forward center, and the insertion of a fresh supply of filling in the shuttle takes place immediately upon the arrival of the lay at its forward center.

A still further feature of the invention contemplates the simplification of the filling feeler mechanism so that it may perform its function of feeling of the filling in the active shuttle, and thereafter be withdrawn from the shuttle to allow a fresh supply of filling to be inserted into the shuttle during the short space of time that elapses between the filling feeling operation and the insertion of the fresh supply of filling in the shuttle.

Further features of the invention will hereinafter appear and be apparent to those skilled in the art. These various features of the invention are embodied in the improved weft replenishing loom herein-after described and particularly pointed out in the appended claims.

In the accompanying drawings illustrating the preferred form of the invention, Figure 1 is a side elevation of a weft replenishing loom showing the application of the improved filling feeler mechanism and the transerrer devices thereto, and Fig. 2 is a perspective view of the transerrer devices and their controlling means.

The loom in connection with which the improved filling feeler and transerrer devices are used may be of any usual or preferred construction, that shown in the illustrated embodiment of the invention being

an ordinary four-color loom. The lay 4 is mounted upon a lay sword 5 pivoted at 6 to the loom frame 7. An oscillatory movement is imparted to the lay by the crank shaft 8 and the pitman 9. On the right hand end of the lay is located a fixed shuttle box 10, and on the left hand end of the lay are located the sliding shuttle boxes 12. A horizontally reciprocating filling magazine 13 is mounted on the right hand end of the loom over the path of movement of the fixed shuttle box 10. This magazine has as many compartments as there are shifting shuttle boxes and each compartment contains a supply of filling of the same color and character as the filling in the corresponding shifting shuttle box. The shifting shuttle boxes are reciprocated vertically in order to present a shuttle containing the proper color of filling to the picker. The reciprocatory movement is imparted to the shifting shuttle boxes 12 by an arm controlled by the pattern mechanism. The connections between the shifting shuttle boxes 12 and its arm 25 consists of a vertically reciprocating rod 16 and a link 17 pivoted at its lower end to the rod 16 and at its upper end to a stud connecting the pattern mechanism arm with an arm 15 controlled through the stud by the pattern mechanism. The filling magazine 30 13 is adapted to move in unison with the shifting shuttle boxes 12 so that, when the lay is on its forward center, a bobbin containing filling of the same color and character as the filling in the active shuttle will be positioned over the fixed shuttle box 10. The reciprocating movements of the filling magazine 13 are imparted to it by the arm 15. The connections between the magazine 40 13 and the arm 15 consists of a bell crank lever 20 pivoted to the frame of the loom, and a link 19 the upper end of which is articulated to the lower arm of the bell crank lever 20 by means of a pin and slot connection in order to regulate the extent of movement of the magazine 13. The lower end of the link 19 is pivoted to the arm 15. The above described arrangement and construction of parts is old and well-known in four-color looms and their operation is understood by those skilled in this art without further explanation.

The improved filling feeler mechanism operates when the filling in the active shuttle is exhausted to a predetermined extent to close an electric circuit, and thereby energize an electro-magnet. The energization of the magnet is utilized to control the transfer devices, which are normally in an inoperative position, and bring them into position to be actuated to insert a fresh supply of filling in the active shuttle. The filling feeler mechanism is situated on the same side of the loom as the transfer devices and consists of a filling feeler 22 and a fill-

ing feeler housing 23. The filling feeler is received in the housing 23 and is adapted to reciprocate forward and backward therein. The filling feeler is spring-pressed toward the lay and is moved forward or away from the lay at the proper times by means of a filling feeler controlling cam 24 mounted upon the cam shaft 25. The connections between the filling feeler and the filling feeler controlling cam 24 for effecting the forward movement of the filling feeler, consist of a bell crank lever indicated generally by the reference character 26, pivoted at 27 to the frame of the loom, a link 28 and a lever 29 pivoted at 30 to the frame of the loom. The upper arm 31 of the bell crank lever 26 is articulated with the filling feeler 22 at 32 by a pin and slot connection. One end of the link 28 is pivoted at 33 to the lever 29, and the other end of the link 28 is articulated 35 with the lower arm 35 at 36 of the bell crank lever 26, by a pin and slot connection. The pin and slot connection 36 between the arm 35 of the bell crank lever and the link 28, affords provision whereby the extent of 40 movement of the filling feeler 22 may be regulated. The function of the filling feeler 22 in feeling of the filling in the active shuttle is performed, as is customary, while the lay is on its forward beat.

In order that the filling feeler 22 may enter the active shuttle 38 to feel of the filling on the bobbin therein, a hole 39 is cut through the front walls respectively of the fixed shuttle box 10 and the shuttle 38. When the filling feeler 22 has performed its function of feeling of the filling in the active shuttle, it is withdrawn from the shuttle before the lay has reached its forward center by the rotation of the filling feeler 45 controlling cam 24. When the filling in the active shuttle 38 has been exhausted to a predetermined extent, that is to say, upon critical exhaustion of the filling, an electrical contact 40 secured to the under side of the filling feeler 22 strikes the electrical terminal 41 secured to the front wall of the fixed shuttle box 10, thereby effecting the closure of an electric circuit. The closing of the circuit operates through appropriate 50 mechanism to cause the insertion of a fresh supply of filling in the shuttle.

In order that the contact 40 may not strike the terminal 41 while the active shuttle 38 is at the opposite end of the lay, that is to say, on the non-detecting forward beat of the lay, the filling feeler 22 is caused to retreat before the lay at this time somewhat more rapidly than on the filling detecting beat. This more rapid withdrawal of the filling feeler 22 before the lay on its non-detecting beat, is effected by the side 43 of the filling feeler controlling cam 24. It will be observed that the construction of the cam 24 is such that the side 44 thereof, which 55

engages the link 28 on the detecting beat of the lay, as is illustrated in Fig. 1, lies at a less distance from the center of the cam 24 than the side 43, which engages the link 28 during the non-detecting beat of the lay. Consequently, the lay reaches a position farther forward on the detecting beat before the withdrawal of the filling feeler 22 than it does on the non-detecting beat; that is to say, while the lay is on the non-detecting beat and the side 43 of the cam 24 is in engagement with the link 28, the side 43 causes the filling feeler 22 to be retracted before the contact 40 and the terminal 41 can come into engagement.

The improved transferrer devices consist of a transferrer hammer 45 pivoted on a pin 46 secured in a box 47 made integral with the magazine slide support 48. A spring 49 encircling the pin 46 normally maintains the transferrer hammer in elevated position. The transferrer hammer 45 is actuated by a transferrer cam 50 to insert a fresh supply of filling in the active shuttle at the appropriate times. The connections between the transferrer hammer 45 and the transferrer actuating cam 50 consist of an angle iron bracket 51 adjustably secured to a downwardly and rearwardly depending portion of the hammer 45, and a cam roll 52 mounted on a roll support 53 pivotally mounted on a pin 54 rigidly secured to and rearwardly projecting from the bracket 51. The roll support 53 is pivoted in unstable equilibrium on the pin 54 so that, during the normal operation of the loom, the cam roll 52 falls out of the path of motion of the active part 55 of the transferrer actuating cam 50, that is to say, when the cam roll 52 is not held in the path of motion of the active part 55 of the cam 50, its weight is such as to cause the roll support 53 to rotate on the pin 54 and permit the cam roll 52 to swing downwardly out of the path of motion of the cam. When critical exhaustion of filling in the active shuttle has been indicated by the filling feeler mechanism, and a fresh supply of filling is to be inserted in the shuttle, the cam roll 52 is moved into its operative position, that is, positioned in the path of movement of the active part 55 of the transferrer actuating cam 50. The operative position of the cam roll 52 is determined by the engagement of a pin 57 projecting laterally from the roll support 53, with a stop pin 58 projecting rearwardly from the bracket 51.

The mechanism for controlling the operation of the transferrer devices consists of an electro-magnet 60 and a cam roll positioning hook 61. When the filling in the active shuttle has been exhausted to a predetermined extent and the electric circuit has been closed, the energization of the magnet

60 operates to draw the hook 61 upward. The upward movement of the cam roll controlling hook 61 causes the lower end 62 thereof to engage the pin 63 projecting laterally from the roll support 53 and thereby 70 rotate the roll support 53 on its pivot 54, so as to bring the cam roll 52 into the path of motion of the active part 55 of the transferrer actuating cam 50. The electro-magnet 60 is secured to the loom frame 7. Situated beneath the magnet is a bracket 65 secured to the loom frame. To the upper end of the bracket 65 is pivoted a lever 66. Secured to the lever 66 and located beneath the poles of the magnet 60 is an armature 80 plate 67. The cam roll controlling hook 61 is secured to the outer end of the lever 66. The energization of the magnet 60 draws the armature plate 67 to itself and thereby raises the roll controlling hook 61. When the magnet 60 is unenergized, the outer end of the lever 66 rests upon the lever support 68 secured to the frame of the loom and the lower end of the hook drops out of engagement with the pin 63. To prevent lateral displacement of the hook 61, a guide plate 69 is provided having a hole through which passes the stem of the hook.

The sequential operation of the improved filling feeler mechanism and transferrer devices is described as follows: The position of the various parts as shown in Fig. 1 indicates that the filling in the active shuttle has been exhausted to a predetermined extent and that the contact 40 on the filling feeler 22 has made an electric contact with the terminal 41 and closed the circuit, thereby energizing the magnet 60. The energization of the magnet 60 has drawn the armature plate 67 into engagement with the poles of the magnet, thereby raising the outer end of the lever 66. The movement of the lever 66 has drawn the hook 61 upward, so that the lower end 62 of the hook has engaged the pin 63 and rotated the roll support 53 so as to bring the cam roll 52 into the path of movement of the dwell 70 of the active part 55 of the transferrer actuating cam 50. The active part 55 of the cam 50 is provided with the dwell 70 in order to prevent a premature insertion of filling into the active shuttle, that is to say, to prevent a fresh supply of filling from being inserted into the shuttle while the feeling end of the filling feeler 22 still remains projected into the shuttle.

It will be observed that the lay as shown in Fig. 1, has not yet reached its forward center and that, consequently, the cam 50 which moves synchronously with the lay actuating crank, will not effect a transfer of fresh filling into the active shuttle until the lay has reached its forward center. This momentary space of time is availed of to withdraw the filling feeler 22 out of

the shuttle 38. It will be observed that the relation of the distances of the connections between the filling feeler and the bell crank lever 26, and between the lever 26 and the link 28 to their respective fulcrums is such that a very small movement upwardly of the link 28 will cause the filling feeler 22 to move a considerable distance relatively thereto. Consequently, although the cam shaft 25 rotates at only one-half the speed of the crank shaft 8, the filling feeler 22 will be withdrawn from the shuttle, after determination of critical exhaustion of filling, before another bobbin can be inserted therein.

The arrangement of the above described parts is such that the critical exhaustion of filling in the active shuttle is determined just previous to the arrival of the lay at its forward center, and the transfer of a fresh supply of filling into the shuttle is effected by a transerrer located rearwardly of the lay immediately upon the arrival of the lay at its forward center. The operation of the transerrer devices therefore takes place while the lay is substantially stationary, that is to say, during the period of dwell of the lay while the crank is passing its forward center or, in other words, during the movement of the lay crank about its forward center. This arrangement of weft replenishing devices and the timing of their operation is believed to be broadly novel.

While the preferred embodiment of the present invention has been specifically illustrated and described, it is to be understood that the present invention is not limited to its preferred embodiment, but that it may be embodied in other constructions of weft replenishing looms within the scope of the invention.

Having thus described my invention, what I claim is:—

1. A weft replenishing loom having, in combination, a lay, a shuttle, an electromagnet, and transerrer devices located rearwardly of the lay and controlled by the electromagnet having provision by virtue of which they are actuated to insert a fresh supply of filling in the shuttle.

2. A weft replenishing loom having, in combination, a lay, a shuttle, a filling supply magazine, and transerrer devices for inserting a fresh supply of filling in the shuttle including a transerrer hammer mounted on the loom frame rearwardly of the filling supply magazine.

3. A weft replenishing loom having, in combination, an electric circuit, a transerrer hammer and a cam, said transerrer hammer having provision by virtue of which it may be actuated by the cam when the electric circuit is closed.

4. A weft replenishing loom having, in combination, a lay, a crank shaft for actu-

ating the lay, a transerrer hammer and connections between the crank shaft and the transerrer hammer constructed and arranged for engagement and actuation by means mounted on the crank shaft, independently of the lay.

5. A weft replenishing loom having, in combination, a lay, a shuttle, a transerrer hammer, a crank shaft, a cam mounted on the crank shaft, and connections between the transerrer hammer and the cam.

6. A weft replenishing loom having, in combination, a shuttle, transerrer devices including a transerrer hammer, a transerrer hammer actuating cam, and a cam roll adapted to be out of the path of motion of the cam during normal operation of the loom and having provision by virtue of which it is moved into the path of motion of the cam upon predetermined exhaustion of filling in the shuttle.

7. A weft replenishing loom having, in combination, transerrer devices including a transerrer hammer, a transerrer hammer actuating cam, a cam roll adapted to be out of the path of motion of the cam during normal operation of the loom, and a magnet for moving the cam roll into the path of motion of the cam upon predetermined exhaustion of filling in the shuttle.

8. A weft replenishing loom having, in combination, a lay, a shuttle, filling feeler mechanism including a filling feeler, an electric terminal connected with the lay, an electric contact mounted on the filling feeler adapted to engage the terminal when the filling in the shuttle has been exhausted to a predetermined extent, transerrer devices for inserting a fresh supply of filling in the shuttle, and means for withdrawing the filling feeler from the shuttle before the insertion of a fresh supply of filling in the shuttle.

9. A weft replenishing loom having, in combination, a lay, a shuttle, filling feeler mechanism including a filling feeler, an electric terminal connected with the lay, an electric contact mounted on the filling feeler, and means for preventing the contact from engaging the terminal when the shuttle is at the end of the lay opposite from the filling feeler mechanism.

10. A weft replenishing loom having, in combination, a shuttle, filling feeler mechanism, transerrer devices located on the same side of the loom with the filling feeler mechanism having a member normally in inoperative position, and electrical connections between the filling feeler mechanism and the transerrer devices having provision when the filling in the shuttle has been exhausted to a predetermined extent, to bring the member into operative position to cause the transerrer devices to be actuated to insert a fresh supply of filling in the shuttle.

11. A weft replenishing loom having, in combination, a lay, a shuttle, a crank shaft for actuating the lay, a filling supply magazine, transferrer devices, a cam mounted on the crank shaft, and connections between the transferrer devices and the cam having provision by virtue of which, when the filling in the shuttle is exhausted to a predetermined extent, the cam actuates the trans-
5 fer devices to transfer the filling from the magazine to the shuttle.

12. A weft replenishing loom having, in combination, a crank shaft, a shuttle, a filling feeler mechanism, means for controlling the filling feeler mechanism, a transferrer hammer, a cam mounted on the crank shaft, connections between the transferrer hammer and the cam including a cam roll normally in inoperative position, and means con-
15 trolled by the filling feeler mechanism adapted on the exhaustion of the filling in the shuttle to a predetermined extent, to bring the cam roll into operative position so as to cause the actuation of the transferrer ham-
20 mer.
25

13. A weft replenishing loom having, in combination, a shuttle box, a shuttle, trans-
30 ferrer devices, an electromagnet for controlling the operation of the transferrer devices, a filling feeler mechanism including a filling feeler adapted to feel of the filling in the shuttle, a terminal on the shuttle box, and a contact on the filling feeler adapted, when the filling in the shuttle is exhausted to a predetermined extent, to engage the terminal to energize the magnet to cause the operation of the transferrer devices.

14. A weft replenishing loom having, in combination, a breast beam, a lay, a shuttle, transferrer devices located rearwardly of the lay, filling feeler mechanism mounted on the breast beam on the same end of the loom on which the transferrer devices are located, and connections between the filling feeler mechanism and the transferrer devices con-
40 structed and arranged to cause the operation of the transferrer devices, when the filling in the shuttle is exhausted to a predetermined extent, on the beat of the lay upon
45 which the filling feeler mechanism operates.

15. A weft replenishing loom having, in combination, a lay, a shuttle, filling feeler mechanism, transferrer devices, and electrical connections between the filling feeler

mechanism and the transferrer devices, said filling feeler mechanism and transferrer devices having provision by virtue of which the filling feeler operation takes place just previous to the arrival of the lay at its forward center, and the operation of the trans-
5 fer devices takes place to insert a fresh supply of filling in the shuttle immediately upon the arrival of the lay at its forward center.

16. A weft replenishing loom having, in combination, a lay, filling feeler mechanism, transferrer devices located rearwardly of the lay, and connections between the filling feeler mechanism and transferrer devices constructed and arranged to cause the operation of the filling feeler mechanism to take place just previous to the arrival of the lay at its forward center, and the transferrer devices to operate immediately upon the arrival of the lay at its forward center upon
60
65
70
75 the same beat.

17. A weft replenishing loom having, in combination, a lay, a shuttle, and transferrer devices for inserting a fresh supply of filling in the shuttle including a pivotally mounted trans-
80 ferrer hammer located rearwardly of the lay.

18. A weft replenishing loom having, in combination, a lay, an electromagnet, trans-
85 ferrer devices located on the loom frame rearwardly of the lay and controlled as to its time of operation by the electromagnet, and actuating means for the transferrer devices.

19. A weft replenishing loom having, in combination, a lay, a crank for actuating the lay, filling feeler mechanism, and trans-
90 ferrer devices located rearwardly of the lay, the filling feeler mechanism and transferrer devices being constructed and arranged to operate in sequential relation on the same beat of the lay during the movement of the lay crank about its forward center.

20. A weft replenishing loom having, in combination, a lay, a shuttle, a feeler, a trans-
100 ferrer located rearwardly of the lay, and connected mechanism operating automatically to cause the feeler to determine critical exhaustion of filling in the shuttle at the end of the forward beat of the lay and immediately thereafter on the same beat
105 to cause the transferrer to insert a fresh supply of filling in the shuttle.

WILLIAM H. RANKIN.
